J. H. BARR.
PAPER FEEDING MACHINE.
APPLICATION FILED SEPT. 15, 1917.

1,285,590.

Patented Nov. 26, 1918.

UNITED STATES PATENT OFFICE.

JOHN H. BARR, OF KANSAS CITY, MISSOURI, ASSIGNOR TO KANSAS CITY FOLDING AND MARKING MACHINE CO., OF KANSAS CITY, MISSOURI, A CORPORATION OF MISSOURI.

PAPER-FEEDING MACHINE.

1,285,590.

Specification of Letters Patent. Patented Nov. 26, 1918.

Application filed September 15, 1917. Serial No. 191,604.

To all whom it may concern:

Be it known that I, JOHN H. BARR, a citizen of the United States, and a resident of Kansas City, in the county of Jackson, and

5 State of Missouri, have invented certain new and useful Improvements in Paper-Feeding Machines, of which the following is a specification.

This invention relates to paper feeding machine, and is designed more especially for feeding slips or labels for use on mail pouches, tie sacks and the like, and my object is to produce a machine for feeding such slips of paper from a pack one at a time, in 15 such a manner that each slip withdrawn from the pack shall be disposed a predetermined distance behind the preceding slip and thus avoid any chance of the fed slips overlapping.

20 With this general object in view the invention consists in certain novel and peculiar features of construction and organization of parts as hereinafter described and claimed, and in order that the same may be fully 25 understood reference is to be had to the accompanying drawing, in which:

Figure 1, is a fragmentary front view of a paper feeding machine embodying my invention.

30 Fig. 2, is a section taken on the line II—II of Fig. 1.

Fig. 3, is a fragmentary top view of the machine with the paper holder broken away.

In the said drawing, 1 is a base provided 35 with side standards 2, one of which is provided with a vertical series of teeth 3.

4 is a transverse shaft journaled in the side standards and equipped with a feed roller 5. Vertically below shaft 4 is a second shaft 6 journaled in said side standards and equipped with a feed roller 7 normally in frictional engagement with feed roller 5, said rollers being preferably of rubber or other compressible material so that they 45 shall be capable of feeding slips of paper or the like between them, and rotatable with and located at the ends of feed roller 7 is a pair of cams 8 for a purpose which herein-after appears. One of the shafts, preferably shaft 4, is adapted for rotation through 50 any suitable means, the preferred method being by means of a manually operable handle 9.

10 is a cross rod connecting the standards 55 2, and mounted upon said cross rod is a rock

frame consisting of a pair of levers 11 connected at their front ends by a rod 12 and at their rear ends by a rod 13, and pivotally mounted at their lower ends on the rod 13 is a pair of bars 14 rigidly secured to and 60 at opposite sides of a boss or holder 15 open at the rear and also open at the front except for a pair of cross plates 16, these cross plates serving as an abutment for a pack of slips 17 of paper or the like. A 65 follower plate 18 fits against the back of said pack of slips and is pivotally carried at the upper end of an arm 19 pivotally supported at its lower end on cross rod 13 and held pressed yielding forward by means of 70 a retractile spring 20, attached at its opposite ends to said arm and to the cross rod 10, the pressure of the follower plate under the pull of spring 20, holding the boss with the arms 14 pressed against the cams 8 for 75 the greater part of each revolution of the feed rollers, it being understood that when the arms and cams are thus engaged, the boss is held repressed sufficiently to prevent engagement between the feed rollers and the 80 foremost paper slip of the pack, but that when the reduced or cut away portions of the cams pass the arms 14, the spring 20 imparts slight forward movement to the box through the pressure of the follower plate 85 therein on the pack of slips, to cause the foremost of said slips to be engaged by the feed rollers so that the latter shall buckle the central portion of such slip forward until it is caught between said rollers as shown 90 in Fig. 2. As this occurs the uncut portions of the cams pass into engagement with the arms 14 and hence repress the same and the box to prevent the rollers from starting the feeding of the next slip of the pack as the 95 end extremities of the one being fed by said rollers pass out of engagement with the latter. Shortly after this occurs the said engaged slip is disposed of by said rollers and the latter have rotated sufficiently to again 100 cause the cut away portions of the cams to pass the arms 14, and permit the spring 20 to readvance the box until the second slip is in engagement with the rollers, when the action described is repeated.

To support the box at the described elevation, the rock frame is provided with a pivoted dog 21 for engagement with the proper tooth 3, the vertical adjustment of the box being determined by reference to a station- 110

ary indicator 22 projecting upwardly and inwardly from one of the side standards 2. From the above description it will be apparent that I have produced a paper feeding machine embodying the features of advantage enumerated as desirable in the statement of the object of the invention, and it is obviously susceptible of modification in minor particulars without departing from the spirit and scope of the appended claims or from the principle of construction involved.

I claim:

1. In a machine of the character described, a frame, a pair of feed rollers journaled in said frame, a holder for a pack of flexible slips, means for holding the holder with the exposed side of the first slip of the pack pressed yieldingly against said rollers, at points between the ends of the slip to cause the latter to be buckled by and between said rollers, and means for periodically imparting relative separating movement to said rollers and holder to disengage the former from the pack of slips.

Copies of this patent may be obtained for five cents each, by addressing the "Commissioner of Patents, Washington, D. C."

2. In a machine of the character described, a frame, a pair of feed rollers journaled in said frame, a box pivotally supported with respect to the frame, a pivotally supported follower arranged in the box and pressing a pack of flexible slips forwardly therein for engagement with said rollers, and means for periodically swinging the box to disengage the foremost of the pack of slips from engagement with said rollers.

3. In a machine of the character described, a frame, a pair of feed rollers journaled in the frame, an indicator in fixed relation to the frame, a pivotally supported box for holding a pack of paper slips adjacent said indicator with the outer side of the first slip of the pack at points between the ends of said slip against said rollers with a yielding pressure, and means for adjusting said box endwise to shift the points of contact between the first slip and said rollers with respect to said indicator.

In testimony whereof I affix my signature.

JOHN H. BARR.
